UNITED STATES PATENT OFFICE.

STEPHEN L. MACIAS, OF POMONA, CALIFORNIA.

VALVE-GUIDE PULLER.

Application filed June 4, 1925. Serial No. 34,825.

This invention relates to valve stem guide pullers.

Practically all internal combustion engines are provided with valve stem guides which snugly fit within bores formed in the cylinder block. The usual procedure for pulling a valve stem guide into place is by means of an ordinary bolt which is extended through the valve stem guide with the head of the bolt resting on a washer placed on the top of a cylinder block and the valve stem guide pulled into place by turning the nut on the bolt. However, in instances when the valve stem is of small diameter, the threads on the bolt are often stripped, due to the tension required to pull the valve stem guide into place.

The object of this invention is to provide a valve stem guide puller which will effectively pull the valve stem guide into place without any danger of stripping threads regardless of the diameter of the valve stem.

Another object of the invention is to provide a valve guide puller which may be quickly applied, for pulling the valve guide into place, and quickly removed from the cylinder block after the guide has been pulled into place.

These objects are accomplished by the disclosure herein set forth by the following description of the accompanying drawings illustrating a practical embodiment of the invention, the novel features thereof being pointed out in the appended claims, in which:

Figure 1 is a fragmentary section of a cylinder block of an internal combustion engine, showing the improved valve stem guide puller as it appears in the first step in the operation of pulling the valve stem guide into place.

Fig. 2 is a view analogous to Fig. 1, showing the valve stem guide puller as it appears when the valve stem guide has been pulled into place.

Fig. 3 is a perspective view of the valve stem guide puller.

Fig. 4 is a transverse section taken on line 4-4 of Fig. 1.

Fig. 5 is a perspective view showing the details of construction of the valve stem guide puller.

Referring by numerals to the accompanying drawings, 10 designates a cylinder block having a cylinder 11, and a piston 12 therein. The cylinder block 10 is of conven-

tional construction and has a port 13 formed therein, adjacent the cylinder 11, which may be either an intake or exhaust port.

A valve seat 14 is formed in the upper face 15 of the cylinder block and a bore 16 in alignment with the valve seat 14 is also formed in the cylinder block, which is adapted to receive a valve stem guide designated at 17. The valve stem guide 17 is of conventional construction and has an internal bore 18 through which the valve stem of the poppet valve extends, and is provided with a flange 19 projecting from the body portion 20.

The valve stem guide puller is generally designated at 21, and consists of a cylinder or sleeve 22, adapted to rest on the upper face 15 of the cylinder block 10 and is provided with a slot 23 for a purpose later referred to.

A head generally designated at 24, has a hub 25 which is adapted to fit within the bore of the cylinder 22 with the shoulder 26 resting on the upper edge of the cylinder 22. An opening 27 is formed in the head 24, through which extends a jack screw 28, having an internal bore 29 and a swedged head 30 in which is formed an opening 31 of smaller diameter than the bore 29, thus forming a shoulder 32 upon which a head 33 of a pulling rod 34 is adapted to engage.

A groove 35 is formed in the lower end of the pulling rod 34 and is adapted to receive a pair of segmental rings 36 clearly shown in Fig. 5, (which engage a shoulder 37). The segmental rings 36 when placed on the rod 34 project beyond the face of the rod 34 and form an abutment adapted to be engaged by a shoulder 38 formed in a collar 39, having a sleeve 40 adapted to fit over the rings 36.

A pin 41 extends radially from the swedged head 30 and projects into the slot 23 and is adapted to hold the screw 28 from rotation. A washer 42 is mounted on the head 24 and a nut 43 is carried by the screw 28.

In operation the valve stem guide 17 is placed in the bore 16 of the cylinder block as shown in Fig. 1, and the valve stem guide puller placed on top of the cylinder block. The rod 34 will drop through the bore 10 in the valve stem guide when the rod and opening 18 are in alignment.

The screw 28 is adjusted by the nut 43 so that the rod 34 will project below the end of the valve stem guide.

The collar 39 is placed on the lower end of the rod 34 in the position indicated by dotted lines in Fig. 1. The segmental rings 36 are then placed in the groove 35 and the collar 39 moved downwardly into positions shown in Fig. 1.

It will be noted that the collar 39 is prevented from moving downward on the rod 34 by the segmental rings 36. By turning the nut 43 the screw 28 will be raised, the action of which will bring the collar 39 into engagement with the lower end of the valve stem guide 17, and by further rotation of the nut 43, the valve stem guide 17 will be pulled into place as shown in Fig. 2, the screw 28 being held against rotation by the pin 41 engaging the sides of the slot 23.

In instances when the valve stem guide fits very tightly within the bore in the cylinder block, the cylinder 22 may have a tendency to move with the nut 43 when it is turned, due to tension and frictional contact. This movement may be prevented by inserting a pin or bar, indicated at 44 through openings 45 in the upper end of the screw 28 and manually held against rotation when the nut 43 is turned.

In order to remove the valve stem guide puller after the valve stem guide has been brought into place, the nut 43 is turned to the left, which will permit the rod 34 to move downwardly. The collar 39 is raised, the segmental rings removed and the collar slipped off the end of the rod, which will permit the rod to be pulled upwardly through the bore in the valve stem guide.

The rod 34 may be made in different sizes to accommodate various sizes of valve stem guides and is adapted to be interchangeable in the jack screw 28, the diameter of the rod being variable while the head 33 remains the same for each rod.

The valve stem guide puller may be employed for removing valve stem guides from the bores in the cylinder block of engines in which the valve stem guides are moved into place by downward pressure, and in operation the device is placed on top of the cylinder block as above described and the valve

stem guide pulled out by turning the nut 43. 50

It will be noted that my valve guide puller is shown as being utilized for inserting valve guides which are pulled into place in the bore 16 from below. However, some of these guides are thrust into place from above 55 and hence my puller may be utilized to dislodge or to remove guides of such character.

From the construction it will be seen that the valve stem guide puller is of simple construction, may be quickly applied for use, 60 will effectively pull the valve stem guide into place and may be quickly removed.

Various changes may be made without departing from the spirit of the invention as claimed. 65

What is claimed is:—

1. A valve guide puller comprising a cylinder, having a slot formed in one side thereof, a head resting on the top of said cylinder, a screw having an internal bore projecting through an opening formed in said head and having a shoulder formed in the lower end thereof, a rod having a head engaging said shoulder, a collar having an opening adapted to fit over the lower end of said rod, said rod having a groove, a pair of segmental rings adapted to be mounted in the groove, said collar having a shoulder adapted to engage said segmental rings, a nut carried by said screw adapted to raise said rod and a pin 80 carried by the lower end of said screw adapted to engage the sides of the slot formed in said cylinder. 75

2. A valve guide puller comprising a member adapted to rest on the top of a cylinder block, a head mounted on said member, a screw extending through said head, a nut engaging said screw, a pulling rod carried by said screw, means for holding said screw against rotation, said pulling rod having an annular groove in the lower end thereof, a pair of segmental rings adapted to fit within said groove and a collar adapted to engage said segmental rings. 85

In testimony whereof I have signed my name to this specification. 95

STEPHEN L. MACIAS.
